UNITED STATES PATENT OFFICE.

FREDERICK MARTEN HALE, OF BROMLEY, ENGLAND.

EXPLOSIVE SHELL OR SIMILAR BODY.

1,224,163.

Specification of Letters Patent.

Patented May 1, 1917.

Application filed December 23, 1914. Serial No. 878,829.

To all whom it may concern:

Be it known that I, FREDERICK MARTEN HALE, a subject of the King of Great Britain and Ireland, and a resident of Bromley, in the county of Kent, England, have invented certain new and useful Improvements in or Pertaining to Explosive Shells or Similar Bodies, of which the following is a specification.

- 10 The present invention relates to shells or similar bodies (hereinafter referred to as shells) intended to be dropped or discharged from air-craft, and of the type in which a detonator is, before the discharge of the shell, arranged in a rear portion of the shell, and is adapted, when the shell has traveled a predetermined distance through the air, to be released so as to be free to be, by the impact of the shell, moved forward in relation to the body of the shell and into contact with a fixed firing element.
- 15 20 25 30 35

In order that greater safety of storage and transport may be insured it is advisable that the detonator should be placed into position only just before the shell is discharged from the air-craft. Now this invention, which consists in the various features set out in the claims hereinafter contained, has for object the provision of shells of the aforesaid type having a construction such that the detonator can be very easily placed into position immediately before the shell is required for use, without the delay and inconvenience occasioned by disassembling the detonator-releasing mechanism.

The invention is illustrated by the accompanying drawings, of which Figure 1 shows in longitudinal section the rear portion of an example of a shell of the aforesaid type constructed in accordance with the invention, Fig. 2 shows in elevation the detachable part of the tail portion of the shell when detached from the shell for the purpose of securing the detonator thereto, and Fig. 3 shows in elevation the detonator and the detonator-holder. Figs. 4 and 5 and Figs. 6 and 7 illustrate respectively two methods of securing the detonator to the detonator-holder alternative to that illustrated by Figs. 1 to 3, Figs. 4 and 6 being longitudinal sectional views of the detonators and detonator-holders shown in elevation in Figs. 5 and 7 respectively.

In the shell illustrated by Fig. 1 the mechanism for releasing the detonator after the shell has traveled a predetermined distance

from the air-craft is like that described in the specification of my Patent 1,141,540, with reference to Figs. 1 and 2 of the drawings thereof, but it will be obvious that any other suitable mechanism may be used for the same purpose if desired.

For the purpose of describing the present invention it will therefore be sufficient to state that in order to release the detonator 3, the releasing spindle 6 is withdrawn into a position in which it does not support the balls 4, 4, in positions in which they project through holes in the detonator-holder *f* into recesses in the wall of the part *b* of the tail portion of the shell.

The tail portion of the shell comprises two parts *a* and *b*, of which *a* is normally secured to the body of the shell and has mounted therein the tube containing the detonator spring 7 and the firing pin 8. The part *b* has mounted therein the detonator-releasing mechanism and normally the detonator-holder *f*, and is adapted to be secured to the part *b* by means of the nut *c*. For this purpose the part *b* is adapted to fit into the part *a* and is provided with a shoulder *e*, which forms an abutment for a corresponding shoulder *d* formed in the nut *c*, and the part *a* is provided with a screw-thread adapted to be engaged by a corresponding screw-thread on the nut *c*.

It will be obvious that in order to place a detonator into position prior to the discharge of the shell from an air-craft it is necessary only to screw back the nut *c*, to detach the part *b* from the part *a* (Fig. 2), to attach the detonator 3 to the detonator-holder *f*, and to secure the part *b* again to the part *a* by screwing down the nut *c*.

In the example shown in Figs. 1, 2, and 3 the detonator-holder is formed with an annular protuberance *g* and the end of the detonator 3 is split to form spring members *h* which are provided internally with projections at their ends. In order to attach the detonator 3 to the holder *f* it is necessary only to press the detonator on the holder until the projections on the spring members engage behind the protuberance *g* on the detonator-holder.

According to the method of attaching the detonator to the detonator-holder illustrated by Figs. 4 and 5 the end of the detonator 3 is so shaped as to engage with the detonator-holder *f* in the manner of a dove-tail joint.

According to the method illustrated by

Figs. 6 and 7 the detonator-holder *f* is provided with an annular screw-threaded projection *l* and the detonator *3* is split at one end to form spring members *h* which are provided internally with projections screw-threaded to correspond to the thread on the detonator-holder. The relative dimensions of the detonator and of the detonator-holder are such that when the detonator is screwed 10 on to the detonator-holder the spring members *h* are forced open until the threads disengage, when the spring members cause the projections thereon to spring into the recess behind the annular projection *l* on the detonator-holder *f*, and thereby to attach the 15 two parts together.

It will be seen that according to any of the three methods hereinbefore described for attaching a detonator to a detonator-holder, 20 lateral movement of the detonator, or of the spring members thereof, in relation to the detonator-holder is required in order to detach the detonator from its holder, and therefore in order to prevent the possibility 25 of the occurrence of such detachment when the detonator has been placed in position in the shell, the bore of the part *a* of the tail portion of the shell is such as to prevent lateral movement of the detonator, or of the 30 spring members thereof, sufficient to detach the detonator from the detonator-holder.

It will be obvious that methods for attaching the detonator to the detonator-holder other than those hereinbefore specifically 35 described with reference to the drawings may be employed without departing from the scope of the invention.

What I claim is:-

1. A shell adapted for discharge from air-craft and comprising a body portion, a tail portion adapted for ready disconnection from and connection to said body portion, a fixed firing element located in and secured to said body portion, a detonator adapted to 40 be fired by impact thereof against said fixed firing element, and mechanism carried by said tail portion and removable therewith from said body portion and in connection with said detonator and adapted, when the shell has traveled a predetermined distance through the air, to free said detonator to be moved forward in relation to said body portion and into contact with said fixed firing element by the impact of said shell, said detonator and said mechanism being adapted for ready connection together and the connection of said tail portion to said body portion being adapted to allow of said ready connection of said detonator with said mechanism on the disconnection of said tail portion from said body portion without the disassembling of said mechanism.

2. A shell adapted for discharge from air-craft and comprising a body portion, a tail portion adapted for ready disconnection.

from and connection to said body portion, a fixed firing element located in and secured to said body portion, a detonator adapted to be fired by impact thereof against said fixed firing element, and mechanism carried by 70 said tail portion and removable therewith from said body portion and including a spindle in connection with said detonator and adapted to be rotated by a vane device and thereby caused, when the shell has traveled a predetermined distance through the air, to free said detonator to be moved forward in relation to said body portion and into contact with said fixed firing element by the impact of said shell, said detonator and 75 said spindle being adapted for ready connection together and the connection of said tail portion to said body portion being adapted to allow of said ready connection of said detonator with said spindle on the disconnection of said tail portion from said body portion without the disassembling of said mechanism.

3. A shell adapted for discharge from aircraft and comprising a body portion, a tail portion adapted for ready disconnection from and connection to said body portion, a fixed firing element located in and secured to said body portion, a detonator holder, a detonator adapted to be fired by impact thereof against said fixed firing element and adapted for ready engagement with said detonator holder, and mechanism carried by and removable with said tail portion and including a spindle engaging said detonator holder and adapted to be rotated by a vane device and thereby caused, when the shell has traveled a predetermined distance through the air, to free said holder to enable said detonator to be moved forward in relation to said body portion and into contact with said fixed firing element by the impact of said shell, the connection of said tail portion to said body portion being adapted to allow of said ready engagement of said detonator with said holder on the disconnection of said tail portion from said body portion without the disassembling of said mechanism.

4. A shell adapted for discharge from air-craft and comprising a body portion, a forward tail portion secured to said body portion, a rear tail portion adapted to be readily disconnected from and connected to said forward tail portion, a detonator located within said forward tail portion, a detonator-holder detachably engaging said detonator, a fixed firing element, and mechanism carried by and removable with said rear tail portion and engaging said detonator-holder and adapted, when the shell has traveled a pre-determined distance through the air, to free said holder to enable said detonator to be moved forward in relation to said body portion and into contact with said fixed firing element by the impact of the shell.

5. A shell adapted for discharge from aircraft and comprising a body portion, a tail portion adapted to be readily disconnected from and connected to said body portion, a 5 movable firing element, a holder detachably engaging said movable firing element, a fixed firing element, and mechanism carried by and removable with said tail portion and engaging said holder and adapted when the 10 shell has traveled a predetermined distance through the air to free said holder to enable said movable firing element to be moved forward in relation to said body portion and into contact with said fixed firing element 15 by the impact of the shell.

6. A shell adapted for discharge from aircraft and comprising a body portion, a tail portion adapted to be readily disconnected from and connected to said body portion, 20 a detonator, a detonator-holder detachably engaging said detonator, the engagement between said holder and said detonator being such as to require lateral movement for their disengagement, a fixed firing element, 25 and mechanism carried by and removable with said tail portion and engaging said detonator-holder and adapted, when the shell has traveled a predetermined distance through the air, to free said holder to enable 30 said detonator to be moved forward in relation to said body portion and into contact with said fixed firing element by the impact of the shell, the portion of the shell containing 35 said detonator and said holder being so formed as, when said detonator and said

holder are located therein, to prevent said lateral movement necessary for the disengagement of said detonator from said holder.

7. A shell adapted for discharge from aircraft and comprising a body portion, a tail 40 portion adapted to be readily disconnected from and connected to said body portion, a movable firing element, a holder detachably engaging said movable firing element, the engagement between said holder and said 45 movable firing element being such as to require lateral movement for their disengagement, a fixed firing element, and mechanism carried by and removable with said tail portion and engaging said holder and adapted, 50 when the shell has traveled a predetermined distance through the air, to free said holder to enable said movable firing element to be moved forward in relation to said body portion and into contact with said fixed firing 55 element by the impact of the shell, the portion of the shell containing said movable firing element and said holder being so formed as, when said movable firing element and said holder are located therein, to prevent 60 said lateral movement necessary for the disengagement of said movable firing element from said holder.

Signed at London, England, this 4th day of December, 1914.

FREDERICK MARTEN HALE.
